US0D1026179S

(12) **United States Design Patent** (10) Patent No.: **US D1,026,179 S**
(45) Date of Patent: ** May 7, 2024

(54) **CONNECTOR**

(71) Applicant: **Mercury Plastics LLC**, Middlefield, OH (US)

(72) Inventors: **Scott R. Gardner**, Chagrin Falls, OH (US); **Russell Clayton**, Gladwin, MI (US)

(73) Assignee: **Mercury Plastics LLC**, Middlefield, OH (US)

(**) Term: **15 Years**

(21) Appl. No.: **29/850,392**

(22) Filed: **Aug. 19, 2022**

Related U.S. Application Data

(63) Continuation of application No. 29/721,400, filed on Jan. 21, 2020, now Pat. No. 961,738, which is a continuation of application No. 15/442,011, filed on Feb. 24, 2017, now Pat. No. 10,591,103.
